UNITED STATES PATENT OFFICE.

OKEY M. WHITE AND WILLIAM CHESTER McCULLOUGH, OF MUSKOGEE, OKLAHOMA,
ASSIGNORS OF ONE-THIRD TO ALEXANDER MATHEWS, OF MUSKOGEE, OKLAHOMA.

WRENCH.

1,422,402.

Specification of Letters Patent. Patented July 11, 1922.

Application filed December 11, 1920. Serial No. 439,912.

To all whom it may concern:

Be it known that we, OKEY M. WHITE and WILLIAM CHESTER McCULLOUGH, citizens of the United States, residents of Muskogee, in the county of Muskogee and State of Oklahoma, have invented certain new and useful Improvements in Wrenches, of which the following is a specification.

Our invention is an improvement in wrenches, and has for its object to provide a wrench especially adapted for removing bits from drill stems, wherein a bit engaging portion is provided, and an operating means for rotating the same in the form of an annulus having a hinged section for permitting the entrance of the stem to the bit engaging portion and separated from the said bit engaging portion by a ball bearing upon which the said portion moves.

20 In the drawings:

Figure 1 is a top plan view of the improved wrench,

Figure 2 is a section on the line 2—2 of Figure 1,

25 Figure 3 is a plan view with the handle and cover plate removed and with parts broken away.

Figure 4 is a plan view with parts in section showing the hinged section,

30 Figure 5 is a section on the line 5—5 of Figure 4,

Figure 6 is a section on the line 6—6 of Figure 3.

In the present embodiment of the invention the improved wrench comprises a circular plate or disk 1 having a diametrically extending notch or recess 2 of a width to receive the bit shank, and to prevent turning of the shank with respect to the disk, so

40 that when the disk is turned the bit will also be turned. This disk rests upon a ring 3, being supported from the ring by means of a ball bearing to be presently described, and the ring 3 is a split ring having between its

45 ends an opening or gap adapted to register with the diametrical opening of the disk to receive the bit. This opening or gap may be closed by means of a gate 4. This gate has one or more hinge lugs 5, which are received

50 in notches or recesses 6 in the ring at one end of the split and a pintle pin 7 pivotally connects the lugs to the ring. A bolt 8 is mounted to slide in an opening at the opposite end of the gate from the lugs 5, and this

55 bolt is adapted to engage an opening in the

other end of the split, for holding the gate in place.

The bolt is moved by means of a finger-piece 9. The ring 3 is journaled between the disk 1 and the disk 10 of greater diameter than the disk 1. This disk 10 is annularly recessed or rabbeted to receive the ring 3, as clearly shown in Figure 2, and the ring is thus held between the disk 1 and the disk 10. The disk 10 has a diametrically extending notch 11 of the same size as the notch 2 of the disk 1, and registering therewith, and the two disks are connected together by screws 12 or the like which connect the disks inside the ring.

70 The ring 3 has a ball race in its upper face, the said race being in the form of a pair of annular grooves 13 and 14, spaced apart from each other and parallel. One of the grooves, namely the groove 13, is of greater depth than the groove 14, and of a depth to entirely receive the balls, so that they will be below the level of the upper face of the ring. The groove 14 is of such depth that the balls will be extended above the upper face of the ring, and above a housing plate or ring 16 which is secured to the upper face of the ring 3. This housing plate is of annular formation, and has an arc-shaped groove 17 registering with the groove 14, but of less width, so that while the balls may extend above the surface of the housing ring 16, they cannot escape from the ring. The ends of the grooves 13 and 14 are connected by inclined 80 passages 18, and the balls may pass from one groove to the other by means of these passages.

85 A handle in the form of an arc comprising a body 19 and arms 20 is connected with the bit engaging element, that is the disks 1 and 10, the said arms being connected in any suitable manner, as for instance by the screws 21. The arms 20 are shaped to fit about the ring 13 as shown in Figure 1.

90 In operation the wrench is placed by swinging open the gate and placing the wrench about the bit. Now by means of the handle, the wrench is turned. The weight of the bit is supported by the balls, it being understood that the ring 3 rests on a suitable support. As the balls travel with the bit engaging element they move along one groove and by the inclined passages at 105 the ends to the other.

We claim:

1. A wrench of the character specified, comprising a bit engaging element, and a ring in which the said element is journaled, the ring having a hinged portion adapted to swing upwardly to permit the insertion of the bit into the bit engaging element through the ring, and means for locking said hinged portion in closed position, and a ball bearing arranged between the bit engaging element and the ring, said bearing comprising arc-shaped grooves in the ring, one of said grooves being of a depth to entirely receive the balls of the bearing, and the other being of a depth to extend the balls into engagement with the bit engaging element, said grooves being connected at their ends by inclined passages, said grooves extending from one end of the gate opening to the other the inclined passages being at the opposite sides of the gate opening.
2. A wrench of the character specified comprising a bit engaging element and a ring in which said element is journaled, the ring having a gap, and a hinged portion

adapted to swing upwardly with respect to the gap to permit the insertion of a bit into a bit engaging element through the gap of the ring, means for locking said hinged portion in closed position, and a ball bearing assembly arranged between the bit engaging element and the ring, said ball bearing assembly including arcuate raceways at each side of the gap.

3. A wrench of the character specified comprising a bit engaging element, and a ring in which said element is swiveled, said ring having a split or gap, a gate hinged at end in said gap and adapted to swing upwardly to permit the insertion of the bit into the bit engaging element through said gap, and antifriction means between the bit engaging element and the split ring, said antifriction means including parallel arcuate grooves in the upper face of the ring said grooves beginning at each side of the gap and communicating with each other by a curved passage at such beginning points.

OKEY M. WHITE.

WILLIAM CHESTER McCULLOUGH.
